(57) **CLAIM**

The ornamental design for a surveillance camera, as shown and described.

DESCRIPTION

FIG. 1 is a top, front, left side perspective view of a surveillance camera, showing our new design;

FIG. 2 is a bottom, rear, right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a top, front, right side perspective view thereof shown in a used condition with a bracket in broken lines.

The dot-dashed broken lines form the boundary of the claimed design. The even dashed broken lines shown in the drawings are included for the purpose of illustrating portions of the surveillance camera and environmental structure of a bracket in FIG. 9 that form no part of the claimed design.
